STOKER MECHANISM HAVING A PULSATORY GRATE

Paul O. Kock, Columbus, Ohio, assignor to Bituminous Coal Research, Inc., Pittsburgh, Pa., a corporation of Delaware

Filed May 24, 1957, Ser. No. 661,376
5 Claims. (Cl. 122—376)

This invention relates to a new stoker mechanism having a pulsatory grate for the effective burning of coals and other solid fuels including bituminous coals with caking or swelling characteristics. More particularly, this invention pertains to new automatic stoker units having a continuous fluid-cooled grate surface which is caused to pulsate with a relatively small magnitude low frequency movement to slide a fuel bed thereover without turnover thereof.

Stoker mechanisms made in accordance with my invention may be utilized for the automatic burning under varying heat demand loads of diverse solid fuels including bituminous coals having caking or swelling characteristics, or having high ash or low ash-softening temperature characteristics, continuously, uniformly and efficiently. If desired, my new stoker mechanism may be constructed as a removable unit to be inserted in the firebox of a suitable boiler or my new construction may be fabricated as parts for assembly on the site where it is to be used. Preferably, cooling is accomplished in my new stoker mechanism by water through connections if desired, with the water space in a heater, furnace, or boiler. The grate in my new stoker mechanisms is continuous and relatively smooth so that a fuel bed may be caused to move thereover without turning over or materially disturbing the arrangement of particles therein. Moreover, the grate bars are relatively short and of a design which inhibits warping and other difficulties. Direct contact between cooling tubes and fuel bed is avoided by such grate bars, those at the ash or front section of the grate being inclined at an angle to the remainder of the grate surface for assistance in maintaining a desired depth of fuel bed. A substantially straightline pulsation preferably of relatively small magnitude and low frequency is imposed upon the grate to assist in advancing a fuel bed thereon. An economical drive both for such pulsation and for feeding fresh fuel to the grate may be provided pursuant to my invention. A wind box is preferably fixed to the underside of the grate for movement therewith and is laterally partitioned for regulation of the quantity of air supplied upwardly through the grate to the respective longitudinal sections thereof for more effective control, if desired, over combustion conditions.

Such new stoker mechanisms of my invention may readily be constructed, provide long life and efficient burning in the course of operation even with bituminous coals having troublesome characteristics. In addition, such new stoker mechanisms have relatively few moving parts, are simple to adjust, are easy to maintain and are capable of giving long, trouble-free and relatively low cost operation. Other objects, features and advantages will be apparent from the following description and from the accompanying drawings, which are illustrative principally of one embodiment of my new stoker mechanism, in which

FIGURE 1 is a side view, partly in section, of one embodiment of a new stoker mechanism unit of this invention installed in a water tube boiler;

FIGURE 2 is a side view on a somewhat larger scale of the stoker mechanism unit embodiment shown in FIGURE 1, with parts broken away and partly in section;

mechanism illustrated in FIGURE 2 with a cover sheet therefor partly broken away;

FIGURE 4 is a plan view of a pulsatory drive mechanism illustrated in FIGURE 3 with the fuel hopper feed mechanism removed and as viewed from a horizontal plane passing generally through line IV—IV on FIGURE 2;

FIGURE 5 is a view on a larger scale taken generally along line V—V of FIGURE 2;

FIGURE 6 is a further larger scale view similar to the left-hand side of the view shown in FIGURE 5 but with the sectioning plane through bolting means used to secure grate bars to the grate;

FIGURES 7 and 8 are respectively side and plan views of an entry grate bar used in the illustrated stoker mechanism grate;

FIGURES 9 and 10 are respectively a side view in medial section and a plan view of a combustion air grate bar utilized in the illustrated stoker mechanism grate;

FIGURES 11 and 12 are respectively side and plan views of a discharge grate bar used in the illustrated stoker mechanism grate; and

FIGURE 13 illustrates a modified drive for the pulsation movement of a stoker mechanism made in accordance with this invention.

Referring to the drawings, a new stoker mechanism 10 of my invention is shown having a water-cooled pulsatory grate 11 and a fuel feed and drive mechanism 12 in the form of an integral unit for the firebox of a boiler 13. Boiler 13 is schematically shown and, for the purpose of illustration, may be a water tube type like that shown in my copending patent application Serial No. 603,088, filed August 9, 1956, now Patent No. 2,827,023. Boiler 13 as shown is provided with a regulatable blower assembly 13a to supply combustion air under pressure to stoker 10 and, if desired, a regulatable induced fan stack draft mechanism 13b may also be provided.

Stoker 10 may be mounted on wheels for readiness of insertion as a unit in a boiler or it may be assembled in situ. In the illustrated embodiment, after stoker 10 is in place, an upper transverse header pipe 14 is connected by a pipe 15 having a flexible section 16 to a boiler pipe 17. In like manner, a lower transverse header pipe or manifold 18 is connected through a pipe 19 having a flexible section 20 to a boiler pipe 21. The boiler pipes 17 and 21 open into the water space of boiler 13 with water circulation preferably being into manifold 18, thence through longitudinally extending grate cooling tubes 22 and out of manifold 14, returning to the boiler water system through pipe 17. The cooling tubes 22 extend longitudinally and parallel to one another and the respective upper and lower ends of such cooling tubes 22 communicate with the interiors of the manifolds 14 and 18. The presence of the flexible pipe lengths 16 and 20 permit grate 11 with its transverse headers 14 and 18 and its cooling tubes 22 to be moved back and forth virtually with straight line motion through a distance of relatively small magnitude at a relatively low frequency without interfering with the flow of cooling fluid through the grate 11 or boiler 13.

Stoker 10 is provided with a rigid structural frame having horizontal members 23 and vertical members 24, the rearward end 25 of such frame being enclosed by cover sheets 25a and serving as a driven compartment for the pulsatory movement imposed upon grate 11. Suitable welding and bolting means are utilized to fasten the respective portions of the frame together and to connect such frame, if desired, to the boiler 13 itself after stoker 10 has been installed. The upper sides of the fixed frame of stoker 10 are bounded by side plates 26, the upper edges of such side plates being sloped downwardly in a forward direction so as to be substantially parallel

to the slope of grate 11. In the illustrated embodiment, grate 11 may be provided with a six degree slope from the horizontal to avoid any steam binding in the horizontal reach of the cooling tubes 22. The side plates 26 are parallel and extend for substantially the entire length of grate 11, terminating adjacent an ash pit 27 at the forward end of the firebox of the boiler 13. Ash pit 27 may be provided with a remotely controllable conveyor 27a to provide for mechanical removal of ashes. Each side plate 26 is adjacent a respective side wall 28 in the firebox of boiler 13 so that whatever solid material may fall from a fuel bed on grate 11 will fall in and close the space between such respective side plates 26 and adjacent side walls 28.

Grate 11 is provided with a frame having longitudinal-ly extending angles 29 affixed to cross angles 30. The longitudinal angles in turn have the flanges thereof extended upwardly by flange extensions 31, the lower edges of which are welded to the angles 29 respectively. Cross members 32 of T-shape in the illustrated embodiment are welded to the vertical flanges of the cross angles 30 and like T-member 34 at the entry end 33 of the frame of grate 11 is supported at the ends by extensions 31.

Transverse angles 35 and 40 are welded at the ends to side extensions 31. Flexure plates 36 and 37 are provided and fastened at the respective bottoms thereof to respective cross members 38 of the rigid stoker frame, bars 39 being utilized to serve as bolting pads with the lower ends of the respective flexure plates 36 and 37 secured between such bars 39 and the cross members 38 as shown in FIGURE 2. The flexure plates are substantially vertical and support grate 11 for alternate pulsation movement and rests without movement between such pulsations in the course of a continuous operation of stoker mechanism 10. The upper ends of the respective flexure plates are bolted to cross angle 40 and to the foremost T member 32, keeper bolting bars 41 being employed with suitable bolts, lock washers and nuts for the purpose of movably mounting grate 11 on the flexure plates 36 and 37. Instead of grate 11 being mounted on flexure plates 36 and 37 it may, if desired, be suspended from hangers pivotally connected to the framework of boiler 13 or its foundation.

The cooling tubes 22 are welded around their respective ends to the manifolds 14 and 18 and the horizontal reach of such tubes is supported by and rests upon the T-shaped members 32 and 34 and upon angle 35. Grate bars 42 which may be made of cast iron and side grate bars 43 are positioned in cross rows around the upper portions of tubes 22 and in the longitudinally extending spaces adjoining the outsides of tubes 22 inclusive of the spaces on the inner sides of the respective extensions 31 of the grate frame. Each such grate bar is provided with a depending portion 44 which is upwardly drilled and tapped in registry with openings in the members 32, 34 and 35 so that socket-head bolts 45 may be passed through such openings in such cross members to respectively threadably engage such grate bars. Lock washers 46 are also so provided so that as the bolts 45 are tightened the respective rows of grate bars 42 and 43 are drawn tight against the cooling tubes or tubes 22 adjoining them. The side of such bars adjoining any such tube 22 is provided with a fillet 47 conforming to the curvature of the adjoining portion of the cooling tube 22 upon which the respective grate bar seats. Preferably, a heat conducting breakable cement or other heat conducting material may be placed between the fillet 47 and the tubes 22 in the course of assembling a new grate 11, for increased heat transmission through the intersurface area. The heads of the respective grate bars 42 and 43 broaden out as shown in FIGURES 5 and 6 and are separated from adjoining grate bars by a slight space 48 to take care of expansion and contraction which occurs in the course of use of such a device. Grate bars 43 along the sides of grate 11 have a laterally outwardly extend-

ing flange 49 to cover the space between the sides 31 of the grate 11 and the side plates 26 to keep material from passing into the space between the respective members 31 and 26. If desired, a flexible seal, like strip 26a, may also be inserted in such space. It will thus be noted that the surface 50 of grate 11 upon which the fuel bed lies is continuous and acts as a unit. Surface 50 is made up of a plurality of grate bars 42 and 43 placed in side-by-side cross rows and in end-to-end columns which move as an entirety in the course of the relatively straight-line pulsatory movement of grate 11.

The grate bars 42 and 43 are differently formed in the illustrated embodiment for the respective transverse row sections A of the grate. Thus, in the entry section, the grate bars 42a and 43a are imperforate and have upper surfaces inclined downwardly and forwardly with a large transverse recessed portion 51 on the underside thereof to fit over the top of manifold 14 and a rearward apron 52 to fit closely beneath the delivery end of feed tubes 53 in the fresh fuel feed mechanism 12. In the next transverse section B, grate bars 42b and 43b toward the rear of grate 11 are imperforate like the entry section grate bars (42a and 43a) so that that portion of the fuel, like bituminous coal, resting on grate bars 42b and 43b and also on bars 42a and 43a tends to give up its volatiles while in those portions of the surface 50 of grate 11. Such volatiles released from the fuel bed will quickly be burned in the hot gases generated in the firebox and passed through the boiler in the course of its use.

Undergrate combustion air grate bars 42c and 43c are in the first combustion air section, like grate bars 42d and 43d are in the second transverse combustion air section and a still further like row of combustion air grate bars 42e and 43e is in the penultimate transverse section. These combustion air grate bars (see FIGURES 9 and 10) are perforate in that the downwardly extending stems 44 thereof are cored leaving skirt portions 44a between which combustion air may rise before entering and passing through tuyere openings 54 into a fuel bed resting on such portions of surface 50. Such openings 54 preferably are inclined toward the front of grate 11. In the foremost transverse section of the illustrated embodiment, the grate bars 42f and 43f (see FIGURES 11 and 12) are imperforate and shaped so that the extreme end thereof is a forwardly and upwardly extending flange 55 while the depending portion 44f is curved downwardly to conform to the curve at the front ends of the cooling tubes 22, a bolt opening 56 being provided to pass alongside such tubes and fasten that end of the grate bars 42f and 43f to a cross angle bar 57 by means of bolts, lock washers and nuts passing between the respective cooling and support tubes 22. The upward inclination of the flanges 55 across the width of surface 50 assists in maintaining a fuel bed of the desired thickness and in discharging ash from grate 11 into ash pit 27 as the fuel bed is fed forwardly on grate 11 during the pulsatory movements thereof.

Combustion air may be supplied to the transverse row sections marked "C," "D" and "E" having the respective grate bars with the respective suffixes "c," "d" and "e" in the foregoing description. Such combustion air reaches such sections of the grate from a plenum or wind box 58. Wind box 58 has an outer shell 59 and is internally laterally divided by partitions 60 and 61. Flanged openings 62 in the two forward compartments communicate with a stationary combustion air duct 63, duct 63 having a flanged registering opening opposite each of the flanged openings 62. Tubular sleeves 74 which may be made of fiberglass impregnated with a material like neoprene extend between the flanged openings in 63 and the respective openings 62 to form respective flexible sealed connections so that movements of grate 11 do not move duct 63. Moreover, the branch openings in duct 63 in registry with openings 62 respectively may be provided with dampers to apportion air

respectively supplied to the compartments C and D. Further regulation may be obtained, if desired, by the employment of an automatic damper in the circuit of a blower fan 71 used to supply combustion air to duct

63. And, in the illustrated embodiment an auxiliary branch duct 72 connected to duct 63 may be opened and used to provide overfire combustion air to the firebox through parallel transversely spaced nozzles 73.

The partitions 60 extend from side-to-side of box 58 and from the bottom thereof to a respective cross angle 64 in the upper rectangular structural rim 65 around the open top of compartments C and D in box 58. The horizontal flanges of the angles of frame 65 engage mating surfaces on the underside of the frame of grate 11 so that box 58 may be secured to the frame of grate 11 by suitable bolts and nuts. As a consequence, movement of grate 11 causes wind box 58 to move therewith since it is supported by and depends from grate 11. Partition 61 is provided with an opening 66 for which there is a hinged door 67 which normally is kept partially open by an adjustable spacing member 68. Combustion air entering opening 62 of compartment D will pass into the fuel bed resting on the grate bars 42c and 43c and also will pass through opening 66 into section E when door 67 is open and then into the fuel bed through the openings in grate bars 42e and 43e.

Fresh fuel is fed across the entire width of grate 11 to the entry section grate bars 42a and 43a thereof by fuel feeder mechanism 12. As shown, the feeder mechanism is provided with an enclosed cubical frame 75 open at the top for the receipt and support of a transversely extending chute 76, the lower end 77 of which substantially closely and separately embraces a plurality of parallel feed screws 78 inclined downwardly in a forward direction. A hopper 79 may be supported above chute 76 by frame 75 and be provided at the top with an opening 80 to which a solid fuel like bituminous coal may be supplied manually, or automatically as by means of an automatic conveyor. The forward end of each feed screw 78 is separately enclosed within a feed tube 81 as a continuation of the chute 76. The feed tubes 81 fit the screws rather closely and at least one full flight at the forward end of each screw 78 is within its tube 81 to act as a fire wall and inhibit any burning back into chute 76. To assist therein and provide relief against any binding tendency, the feed screws 78 may be tapered in a rearward direction away from grate 11 or the diameter or pitch of the flights more directly under the chute 76 may be made somewhat smaller. A shaft 83 on each screw 78 extends through a rear wall 84. The shafts 83 are held in place by suitable thrust bearings 86. To the forward end of each shaft 83 there is affixed a sprocket 87, a shear pin 88 being used to connect it to its respective shaft 83. Hence, if any feed screw 78 should jam, it would shear its own pin 88 only and the sprocket thereof would rotate idly without immobilizing the other feed screws 78. A chain 89 engages all of the sprockets, a guide 90, an idler roller 91 and a drive sprocket 92 so that as drive sprocket 92 turns, fresh fuel from hopper 76 is fed on to the rearward or entry end "A" of grate 11 by the screws 78. Such screws as shown are of alternately opposite hands so all feed fuel forwardly when rotated by gear 92. As fresh fuel is fed by mechanism 12, it passes through a refractory lined tunnel 93 which bridges the space between the end of the delivery tubes 81 and the firebox opening 94 in boiler 13.

In the drive compartment 25 of mechanism 12, an electric motor 95 is fastened to a slidably adjustable base 96 secured to the frame of stoker mechanism 10 so that the desired tension may be imparted to a belt 97 used to drive a driven pulley 98. Driven pulley 98 is mounted on a shaft 99 journaled in bearings held by rigid brackets 100, the other end of shaft 99 being provided with a pulley 101 which serves to drive a further belt 102. Belt 102 also engages a large pulley 103 mounted on a shaft

104 journaled in the frame of compartment 25. A pulsation cam 105 is affixed to shaft 104, such cam having a smoothly contoured cam rise portion 106 and fall portion 107 on its periphery.

5 Bearings 108 on the brackets 100 support a cross shaft 109 from which a cam lever 110 is pivotally supported, the lower end of lever 110 being provided with a cam follower roller 111 held against the periphery of cam 105 by a spring 112. Pull rods 114 are attached at their forward ends to grate 11 and are provided with spring retainers 114a at their respective rearward ends. The pull rods 114 pass through brackets 100a rigidly connected to the main brackets 100 and a spring 116 surrounds each rod 114 in compressed relation between its respective bracket 100a and retained 114a to maintain grate 11 in pressing connection with the periphery of cam 105 through a connector 113 and lever 110. Connector 113 is provided with a registering hole to receive a pivot bolt 115 which passes through registering openings in lever 110 to pivotally connect member 113 to cam lever 110. The movement in operation of connector 113 is preferably so small that grate 11 is virtually reciprocated in a straight line. The forward end of connector 113 is rigidly connected to an anglepiece 117 which in turn is fastened to cross angle 40 between the laterally spaced flexure plates 36. Hence as connector 113 is moved back and forth by the rotation of cam 105, grate 11 reciprocates with a pulsatory short straight-line movement so that a fuel bed slides over surface 50 during operation toward discharge end "F" without forwardly jumping or turning over the bed or portions thereof. The rise portion 106 of cam 105 is preferably smoothly contoured to provide smooth acceleration and deceleration during the stroke of connector 113 in each direction, with the greatest travel per given time occurring at the "ash pit" ends of respective strokes. In this way, grate 11 has its maximum speeds as it nears the final portion of its forward stroke toward the ash pit 27 again as it initiates its return stroke from such forwardmost position. Further, although surface 50 of grate 11 is provided, as shown, with about a six-degree slope away from the horizontal extending downwardly in a forward direction in the embodiment shown to insure avoidance of steam binding, grate 11 will function to move the fuel bed during a pulsatory portion of an "on" cycle even when grate 11 is horizontal because of such character of the acceleration and speed as the grate is pushed forwardly and then suddenly reversed in direction at the end of such forward travel.

As a non-limiting example only, successful operation 50 may be obtained with a bituminous coal when motor 95 rotates cam 105 at a speed of less than 400 revolutions per minute to cause a back-and-forth movement of grate 11 in the order of preferably less than one-fourth of an inch in each direction. By various means including a combustion control and timer device 118 connected to a power source 119, the fuel feed and pulsatory operation period in an "on" cycle and the "on" cycle duration in stoker mechanism 10 may be respectively and widely varied. Thereby, the length of "on" period and the frequency 55 and length of the pulsatory operation of grate 11 in such an "on" period will correlate to satisfy any heat demand load including holdfires that may be required of stoker mechanism 10.

A gear reducer 120 is pulley driven from shaft 104 by 65 a belt 121. Drive sprocket 92 is connected to the output shaft of gear reducer 120 with the result that chain 89 is moved to feed fresh fuel onto the grate bars 42a and 43a whenever motor 95 is energized to commence a further pulsatory grate movement period. Since the operation of 70 the feed screws 78 is positive, fuel will thereby be supplied uniformly to the grate across the width thereof. In the event that it becomes desirable to insert a tube cleaner in the grate supporting and cooling tubes 22, plugs 128 in manifold 14 respectively opposite the forward ends of each of such cooling tubes may be removed

for that purpose. Further, the rear manifold 18 may be provided with a suitably valved blow-off or drain pipe 129 for use as occasion requires.

An alternate drive mechanism to that in compartment 25 is schematically illustrated in FIGURE 13. In that figure, an electric motor 130 when energized during a pulsatory grate movement period rotates a drive shaft 131 through a flexible coupling 132. Shaft 131 may be mounted in bearings 133. An eccentric 134 is secured to shaft 131 to rotate therewith. A rock shaft 135 is mounted in bearings 136. A rockable eccentric 137 is affixed to shaft 135. A crank arm 138 embraces the eccentrics 135 and 137 to rock eccentric 137 in the illustrated embodiment through an angle such as 90° which is bisected by a horizontal plane through the axis of rock shaft 135. A drive eccentric 139 is also keyed to shaft 135 and has its center angularly displaced by an amount such as 45° from the center of the rocking eccentric 137. Drive eccentric 139 is pivotally connected by a connector 140 to an angle 141 corresponding in function to angle 117. Hence, as shaft 131 is rotated in the direction of arrow 142, the maximum speed of the pulsatory grate (like grate 11) of which angle 141 is a part, will occur during that portion of the stroke in each direction adjoining the foremost position of angle 141 and its grate which is when such grate is farthest from the axis of rock shaft 135. Moreover, such pulsation will be of relatively small magnitude and low frequency and the fuel bed on the grate to which angle 141 is connected will not jump or turn over in the course of such pulsation but will be virtually straight-line motion with smooth speed change transitions throughout and at the ends of the respective strokes where the direction of movement of the grate is changed.

It will be evident that stoker mechanism of my invention may be made with various modifications in the provisions for driving the same and in the elements and parts thereof without departure from my invention. Further, stoker mechanism made in accord with my invention may be used with a variety of different kinds of boilers and other equipment. In some cases, cooling of my new grate may be performed by a gas under pressure rather than by liquid. These and other changes are within the spirit of my invention and the scope of the appended claims.

I claim:

1. In a stoker unit, apparatus comprising, in combination, a stoker frame, a unitary water-cooled pulsatory grate inclined somewhat downwardly toward its discharge end, a grate frame in said grate, a plurality of parallel longitudinally extending cooling tubes mounted on said grate frame, upper and lower manifolding headers connecting the ends of said cooling tubes respectively, flexure plates respectively connected to said stoker frame and to the respective ends of said grate frame to movably support said grate, grate bars in side-by-side transverse row sections and end-to-end columns providing a substantially continuous smooth grate surface, said grate bars being generally T-shaped in cross section and having a depending web to fit between and alongside said cooling tubes, the undersides of the T-heads of said grate bars generally conforming in shape to the adjoining surface of said cooling tubes respectively, heat conductive means in the intersurface area between said grate bars and said cooling tubes respectively, means for rigidly connecting the underside of said grate bars to said grate frame, said grate bars at the entry end of said grate being imperforate, more forwardly transverse row sections of said grate bars being perforate and provided with combustion air discharge tuyeres directed generally upwardly and longitudinally toward the discharge end of said grate, a transverse row section of grate bars at said discharge end having a flange inclined somewhat upwardly and forwardly relative to said grate surface, said grate frame below said transverse row sections of perforate grate bars being divided generally into separate compartments, a com-

partmented wind box suspended from said grate frame, said wind box having compartments generally registering with said compartments in said grate frame, means for supplying bulk combustion air to at least a plurality of said compartments in said wind box, a chute for fresh fuel having parallel longitudinally extending troughs in the bottom thereof, transversely adjoining feed tubes at the forward ends of said troughs overlying the rearmost end of the rearmost row of grate bars, feed screws extending along said troughs and into said feed tubes respectively, adjoining feed screws being of opposite hands, common means for driving all of said feed screws in a fuel feeding direction, shear means respectively connecting said feed screws to said common means, said feed screws having their forward sections fitting closely in said feed tubes and with the rearward portion of said feed screws being of lesser feed capacity, pull rod means adapted to urge said grate toward its rearmost position, a connector rigidly connected to said grate, a cam lever pivotally connected to said connector, a cam to operatively exert force against said cam lever, said cam having a smooth contour periphery including a rise portion adapted to provide greater average speed of movement of said grate at the respective rearmost end of its pulsatory strokes in both directions when said cam is rotating, and means for simultaneously rotating said cam and driving said common means.

2. In a stoker mechanism, apparatus comprising, in combination, a pulsatory grate having an entry end, a plurality of parallel longitudinally extending cooling tubes in said grate, transverse manifolds connecting the respective ends of said cooling tubes, means to support said grate for pulsatory movements thereof, grate bars in side-by-side transverse row sections and end-to-end columns providing a substantially continuous smooth grate surface, said grate bars having a depending portion to fit between and alongside said cooling tubes, said grate bars having filleted undersurfaces generally conforming in shape to the adjoining surfaces of adjoining cooling tubes respectively, said grate bars at the entry end of said grate being imperforate, other transverse row sections of said grate bars being perforate and provided with tuyeres directed generally upwardly and longitudinally toward the discharge end of said grate, a transverse row section of said grate bars at said discharge end having a somewhat upwardly inclined apron, a compartmented wind box suspended below said perforate grate bars, means for supplying combustion air to said compartments in said wind box, a fresh fuel chute at the entry end of said grate having transversely adjoining parallel longitudinally extending troughs in the bottom thereof and feed tubes at the forward ends of said troughs, feed screws in said troughs extending into said feed tubes respectively, a connector rigidly connected to said grate, means for operating said grate including a cam in continuous operative connection with said connector, said cam having a smooth contour periphery including a rise portion adapted to provide greater speed of movement in said grate at the respective end of at least its stroke toward said entry end, and means for rotating said cam, and means for rotating said feed screws, whereby said grate is moved back and forth in a smooth pulsatory virtually straight-line path to advance a fuel bed over said grate surface without jumping or turning over of the same.

3. In a stoker unit, apparatus comprising, in combination, a cooled smooth unitary pulsatory grate, means to support said grate adjacent its ends only for pulsatory movement thereof, a plurality of cooling tubes in said grate, means for circulating coolant through said cooling tubes, a plurality of grate bars in side-by-side and end-to-end arrangement to provide a substantially continuous relatively smooth grate surface, said grate bars being generally shaped on the underside to fit against said cooling tubes, a preponderance of said grate bars being perforate to supply combustion air upwardly therethrough,

a wind box supported by and below said grate to supply said combustion air, said wind box having a transverse partition, a chute for fresh fuel having parallel longitudinally extending troughs in the bottom thereof, feed tubes at the forward ends of said troughs and overlying the grate bars across the entry end of said grate, transversely adjoining feed screws in said troughs extending into said feed tubes respectively, common means for driving all of said feed screws in a fuel feeding direction, breakable means for each feed screw respectively to transmit force to said feed screws from said common means, and smooth contour means operatively connected to said grate to drive said grate back and forth with a relatively short pulsatory substantially straight-line movement.

4. In a stroker mechanism, apparatus comprising, in combination, a longitudinally movable grate having an upper side and an entry end, a plurality of longitudinally extending feed tubes transversely adjoining one another on the upper side of and substantially across the entire width of said grate at the entry end thereof, a plurality of longitudinally extending feed screw relatively closely fitting in at least a part of said tubes, a shaft for each of said feed screws extending in a direction away from said grate, a shearable drive member operatively connected to each of said feed screw shafts, means for feeding solid fuel to the ends of said feed screws farther from said grate, and a common means to move said grate and rotate

said feed screws for synchronized feeding of fuel in a positive manner.

5. In a stoker mechanism as set forth in claim 4, having alternate ones of said feed screws of opposite hands, means whereby said common means drive said feed screws of opposite hands in opposite rotational directions, means for spacing the ends of said feed screws nearer said grate from the firebox zone thereof, and tunnel means extending between said ends and said zone.

UNITED STATES PATENT OFFICE
CERTIFICATION OF CORRECTION

Patent No. 3,005,446

October 24, 1961

Paul O. Kock

It is hereby certified that error appears in the above numbered patent requiring correction and that the said Letters Patent should read as corrected below.

In the grant, line 1, for "Paul O. Koek" read -- Paul O. Kock --; column 4, line 14, after "sections" strike out "A" and insert the same after "section" same line 14, same column; column 8, line 47, for "bare" read -- bars --.

Signed and sealed this 3rd day of April 1962.
